UNITED STATES PATENT OFFICE.

CHARLES E. GODLEY, OF DETROIT, MICHIGAN, ASSIGNOR TO EDMUND'S AND JONES MANUFACTURING COMPANY, OF DETROIT, MICHIGAN, A CORPORATION OF MICHIGAN.

LAMP.

1,101,021.

Specification of Letters Patent. Patented June 23, 1914.

Application filed February 27, 1914. Serial No. 821,360.

To all whom it may concern:

Be it known that I, CHARLES E. GODLEY, a citizen of the United States, and a resident of Detroit, in the county of Wayne and State of Michigan, have invented a new and Improved Lamp, of which the following is a specification.

This invention relates to lamps intended for use in the open exposed to wind and rain, and its object is to provide a lamp wherein the proper ventilation shall be secured and the effect of sudden gusts of air overcome; and to provide a construction in which the parts may be easily assembled, and so securely clamped together that rattling shall be overcome.

This invention consists in the details of construction shown, described and particularly pointed out in the claims.

20 In the drawings, Figure 1, is a side elevation of a lamp in which this invention may be embodied. Fig. 2 is a vertical section through the upper portion or head of Fig. 1. Fig. 3 is a section on the line 3—3 25 of Fig. 2. Fig. 4 is a section on the line 4—4 of Fig. 2. Fig. 5 is a side elevation of the cap. Fig. 6 is a side elevation of the chimney tube and perforated curtain.

Similar reference characters refer to like 30 parts throughout the several views.

My improved construction is shown as embodied in a lamp comprising a font 1, a body 2, having a closed rear end 3 and a flaring front end 4, which may be closed by 35 a lens door 5, that supports the lens 6 in the usual manner. An opening is formed in the upper side of the body to receive a head that comprises a lower section 8, having its lower end turned inwardly to form 40 an annular bearing shoulder 9 whose inner edge may be turned downwardly to form the cylindrical extension 10 that passes through the opening in the body and centers the head in respect thereto. The lower section of the 45 head is also provided with a series of draft openings 11, and has a flaring upper end 12, the edge of which may be turned inwardly to form a bead 13 that may be received by the similarly beaded lower end 15 of the 50 upper section 16 of the head. The upper portion of the section 16 may be constricted to form an edge 17 from which the top 18, having a small central aperture, may be supported, by a series of posts 19 (Fig. 3) 55 provided with the channels 20 in their inner

surfaces, the posts being spaced apart somewhat to form a series of passages 21, for the burnt gases and hot air. A handle 22 may be attached to the head in any desired manner.

Passing longitudinally through the opening in the top of the body is a chimney tube having a cylindrical body portion 23 and a flaring lower end 26, whose outer edge is turned upwardly at 27 to receive and support a curtain 28 which, as shown, is of the shape of the frustum of a cone, and which may have at its upper end the inturned annular flange 29 that bears upon the body 2. The curtain is preferably provided with a series of small perforations 30. The chimney tube is spaced somewhat from the cylindrical extension 10 to form an annular passage through which air entering the openings 11 may pass downwardly into the space inclosed by the curtain 28, and through the perforations 30 into the body of the lamp. The upper portion of the chimney tube fits rather snugly within the edge, 17 of the head, and is provided with a series 80 of peripheral openings 33 that may be formed by striking from the body of the tube the inwardly inclined tongues 34, and by removing portions of the tube above these tongues. Other portions of the tube may 85 be bent inwardly as indicated at 35 to form reinforcing members. The upper end of the chimney tube may extend above the edge 17 and have a closed end 37 that is supported from the body of the tube by a series of 90 posts 38 having ribs 39 thereon corresponding to and are received by the channels 20 in the posts 19 of the head, whereby relative angular movement of the chimney tube and the head is prevented. Between the 95 posts 38 are a series of openings 36, corresponding to the openings between the posts 19. These openings are preferably formed by bending the reinforcing flanges 40 inwardly. The end 37 preferably has a central aperture corresponding to the aperture in the cover 18 of the head, and may have soldered or otherwise, secured to its lower surface a threaded nut 41.

Fitting upon the upper surface of the 105 head 18 is a cap that may be formed of a lower section 43 having a beaded edge 44 that is received by the beaded edge 45 of an upper section 46. The lower section of the cap may be perforated in alignment with the 110

perforations in the parts 37 and 18, and through these perforations the threaded bolt 47 may pass, said bolt preferably having a head 48 that may be soldered to the lower section of the cap.

The parts are assembled by opening the lens door and inserting the chimney tube and curtain from below. The head is then positioned from above, after which the bolt 47 is inserted and the posts rigidly secured together by turning the cap to screw the bolt 47 into the nut 41.

While the chimney tube, cap and curtain are shown applied to a substantially globular lamp body having a flaring front, it is clear that these improvements may be applied to lamp bodies of widely different forms.

Part of the air entering through the openings 11 passes downwardly into the space between the curtain and the chimney tube and part of it passes upwardly into the space between the tube and the head. The downward current is intercepted by the curtain through the small perforations of which it passes rather slowly and regularly by which the effect of sudden drafts is largely overcome. The air is then received in the body of the lamp, from which it passes upwardly into the chimney tube and out through the openings between the posts 38. The upward current of air in the head passes into the chimney tube through the openings 33 and onwardly through the openings 36 with the air coming up through the tube, the tongues 34 serving to direct the air in its course and to prevent back draft down the chimney tube.

It is obvious that many changes may be made in the details of my construction without departing from the spirit of my invention. I do not therefore, wish to be limited otherwise than as indicated by the subjoined claims.

I claim:

1. In a lamp, a sheet metal body having an opening therein, a sheet metal head the lower end of which forms a tight connection with the edge of said opening in the lamp body, said head comprising a top between which and the remainder of the head a series of openings are formed, a chimney tube within the head of less cross-sectional area than that of the lower portion of the head and having a closed upper end and openings just below its upper end to register with the openings in the head, the openings in the chimney tube being at the same level as the openings in the head, and means for securing the upper end of the chimney tube to the top of the head.

2. In a lamp, a body having an opening, a hollow head connecting to the edge of the opening in the lamp body, a top for the head below which the head is provided with a series of peripheral openings, said top pro-

vided with a central opening, a chimney tube within the head of less cross-sectional area than that of the lower portion of the head and having openings at its upper end to register with the openings in the head, said chimney tube having a flaring lower end and a closed upper end provided with a central threaded opening, and a bolt extending through the opening in the top and chimney tube for securing the parts together.

3. In a lamp, a body having an opening therein, a tubular head the lower end of which forms a tight connection with the edge of said opening in the lamp body, said head having a series of perforations and having a constricted upper portion and also comprising a top between which and the remainder of the head a series of openings are formed, said top having a central opening, a chimney tube within the head of less cross-sectional area than that of the lower portion of the head and having openings at its upper end to register with the openings in the head, and having a closed upper end provided with an opening, and means for securing the parts rigidly together, consisting of a screw extending centrally downward from the top of the head into the top of the chimney tube.

4. In a lamp, a body having an opening, a hollow head, the lower end of which forms a tight connection with the edge of the opening in the lamp body, said head having a series of peripheral openings in its lower portion and having a constricted upper portion, a top for the head below which the head is provided with a series of peripheral openings, a chimney tube within the head of less cross-sectional area than that of the lower portion of the head and having openings at its upper end to register with the openings in the head, and also having a series of openings formed therein below the constricted upper portion of the head, said chimney tube having a flaring lower end, a curtain inclosing the chimney and forming a connection between the lower end of the head and the chimney tube, said curtain having a series of small openings formed therein, and a bolt extending through the top and upper end of the chimney tube for securing the parts rigidly together.

5. In a lamp, a body having an opening therein, a tubular head, the lower portion of which is provided with an annular shoulder and a cylindrical extension, the shoulder bearing upon the upper surface of the body and the extension being received within the opening in the body, said head having a series of perforations in its lower portion and having a constricted upper portion and also having a series of openings formed therein above the constricted upper portion, a chimney tube within the head of less cross-sectional area than that of the lower portion of

the head and having openings at its upper end that register with the openings in the head, a curtain inclosing the chimney and having a shoulder that bears upon the inner surface of the body, said curtain forming a connection between the body and the chimney tube and having a series of small openings therein, and means for securing the parts rigidly together.

6. In a lamp, a body having an opening therein, a tubular head the lower portion of which is provided with a shoulder that bears upon the upper surface of the body, said head having a series of perforations therein and having a constructed upper portion, said head also having a series of openings therein above the constricted portion and a top above the openings having a central aperture, a chimney tube within the head of lesser cross-sectional area than that of the lower portion of the head and having openings at its upper end to register with the openings in the head, said chimney tube also having a series of openings therein below the restricted portion of the head and a closed upper end having a central aperture, a curtain inclosing the chimney and having a shoulder that bears upon the inner surface of the body, said curtain forming a connection between the edge of the opening in the body and the chimney tube and having a series of small openings therein, and a bolt extending through the apertures in the top and end of the chimney tube for securing the parts rigidly together.

7. In a lamp, a body having an opening therein, a tubular head the lower portion of which is provided with an annular shoulder and a cylindrical extension, the shoulder bearing upon the upper surface of the body and the extension being received within the opening in the body, said head having a series of perforations in its lower portion and having a constricted upper portion and also having a series of openings formed therein above the constricted upper portion, a chimney tube within the head, of less cross-sectional area than that of the lower portion of the head and having openings at its upper end that register with the openings in the head, said chimney tube also having a series of openings therein below the restricted portion of the head, a curtain inclosing the chimney and having a shoulder that bears upon the inner surface of the body, said curtain forming a connection between the body and the chimney tube and having a series of small openings therein, and means for securing the parts rigidly together.

8. In a lamp, a body having an opening therein, a tubular head, the lower end of which forms a tight connection with the edge of said opening in the lamp body, said head having a series of perforations and having

a constricted upper portion and also comprising a top between which and the remainder of the head a series of openings are formed, a chimney tube within the head of less cross-sectional area than that of the lower portion of the head and having openings at its upper end to register with the openings in the head, means to prevent angular rotation of the head and chimney tube in respect to each other, a curtain inclosing the chimney tube and forming a connection between the lower end of the head and the chimney tube, said curtain having a series of small openings therein, and means for securing the parts rigidly together.

9. In a lamp, a body having an opening therein, a tubular head, the lower end of which forms a tight connection with the edge of said opening in the lamp body, said head having a series of perforations and having a constricted upper portion and also comprising a top between which and the remainder of the head a series of openings are formed, a chimney tube within the head of less cross-sectional area than that of the lower portion of the head and having openings at its upper end to register with the openings in the head and also having a series of openings therein below the constricted portion of the head, means to prevent angular rotation of the head and chimney tube in respect to each other, a curtain inclosing the chimney tube and forming a connection between the lower end of the head and the chimney tube, said curtain having a series of small openings therein, and means for securing the parts rigidly together.

10. In a lamp, a body having an opening therein, a tubular head, the lower end of which forms a tight connection with the edge of said opening in the lamp, said head having a series of perforations and having a constricted upper portion and also comprising a top between which and the remainder of the head a series of openings are formed, said top having a central longitudinal perforation therein, a chimney tube within the head of lesser cross-sectional area than that of the lower portion of the head and having a closed upper end, provided with a perforation therein in alignment with the perforation in the cover portion of the head, said chimney tube having openings therein below the top to register with the openings in the upper end of the head, a curtain bearing against the chimney tube and forming a connection between the lower end of the head, the lamp body and the chimney tube, said curtain having a series of small perforations therein, a threaded bolt passing through the aligned perforations in the cover portion of the head and the cover portion of the chimney tube, and a nut on the bolt whereby the parts may be clamped rigidly together.

11. As an article of manufacture, a chimney tube for a lamp, said tube comprising a cylindrical body portion having a flaring lower end, the other end of the tube having a cover portion formed integrally therewith, the body portion of the tube having therein a series of lateral openings beneath the cover portion, and a series of inwardly inclined deflecting tongues struck from the

body portion and forming a second series 10 of openings below the first series.

In testimony whereof I have signed this specification in the presence of two subscribing witnesses.

CHARLES E. GODLEY.
